UNITED STATES PATENT OFFICE.

ISAAC A. BACKLUND, OF CHICAGO, ILLINOIS.

AUTOMATIC DAMPER-REGULATOR.

1,308,015.

Specification of Letters Patent. Patented June 24, 1919.

Application filed February 19, 1919. Serial No. 278,085.

To all whom it may concern:

Be it known that I, ISAAC A. BACKLUND, a citizen of the United States, residing at Chicago, in the county of Cook and State of Illinois, have invented certain new and useful Improvements in Automatic Damper-Regulators, of which the following is a specification.

This invention relates to automatic damper regulators of the class illustrated and described in U. S. Patent No. 1,276,002, issued August 20, 1918, wherein is employed a hydraulic motor operatively connected to the damper, said motor having a controlling valve which is regulated by steam pressure through the agency of a quantity of mercury.

The object of the present invention is the perfecting of the apparatus by which the mercury is utilized to afford a maximum of efficiency with an economical use of the liquid agent.

With these ends in view the invention consists in certain novel devices, and in the adaptation and combination of the same.

The accompanying drawing is a view shown partly in front elevation and partly in vertical section of a damper regulator embodying my improvements.

The reference numeral 1 designates a steam boiler having a smoke stack 2 provided with a damper indicated by dotted lines 3. Said damper is normally held in its open position by means of a weight 4 attached to an arm 5 of a lever which is connected to the damper spindle 6. The other arm 5¹ of said lever is connected by a chain or cord 7 passing about pulleys 8 and 9 to the underside of a vertically movable frame 10. This frame is connected to and operates in unison with a plunger 11 extending through a stuffing box 12¹ into the cylinder 12 of a hydraulic motor.

Communicating with the cylinder chamber is a pipe 13 connected with a pipe 14 through which water under pressure is supplied to the cylinder and is also connected with a waste pipe 15 through which the water is discharged. The admission and discharge of the water is governed by means of a three-way valve 16 of the rotary type, preferably, provided in a casing 17 to which the aforesaid pipes are connected.

By regulating the valve 16 to admit pressure water into the cylinder 12, the plunger

11 is forced upwardly and acting through the medium of the frame 10 and cord 7 effects a closing movement to the damper 3 in opposition to the weight 4. When the valve is turned to close communication between the pressure water pipe 14 and the cylinder pipe 13 to establish communication between the latter and the waste pipe 15, the water escapes from cylinder 12 to allow the plunger and attached frame 10 to descend, whereupon the weight 4 asserts itself to return the damper to its open illustrated position.

The valve 16 is controlled by connecting the handle 18 thereof by means of a rod 19 with an arm 20 of a lever fulcrumed at 21 and having a heavy body 22 on its other arm 20¹, which acts counter to the weight of the valve-regulating devices which are suspended from the lever arm 20. The valve-regulating devices, like those disclosed in the referred-to patent, comprise a liquid-tight vessel 23 through which extends an upright pipe 23¹ having openings 24 and 24¹ which afford communication with the interior of the vessel.

The vessel is rigidly connected to the pipe 23¹, whose lower end is connected by a T-fitting 25 with a flexible tube 26 extending downwardly and having its lower end connected with a pipe 27 which extends into and terminates adjacent to the bottom of a tank 28. The tank 28 serves as a reservoir for a quantity of mercury or other suitable liquid, indicated by 29.

Connection is had by means of a pipe 30 between the steam space within the boiler 1 and the upper end of the tank 28, whereby the steam pressure acting downwardly in the reservoir tends to force the mercury through tube 26 into the vessel 23.

When the steam pressure is sufficiently high to elevate enough mercury into the vessel to overcome the effective power of the weight 22, the lever 20-20¹ is influenced to impart an opening movement to the valve 16 for the admission of water under pressure from the service pipe 14 to the motor cylinder 12.

When this occurs, an upward movement is imparted to plunger 11, resulting in a closing movement of the damper 3 with a consequent throttling of the furnace draft and a reduction in the steam generation.

The steam pressure would thereupon de-

crease, allowing the mercury to return from vessel 23 into the reservoir with a corresponding action of the valve 16, resulting in the motor being affected to enable the 5 weight 4 to open the damper.

By suitably positioning the body 22 on lever 20—20¹ the power of a quantity of mercury in the vessel 23 may be varied to regulate the apparatus to control the boiler 10 steam pressure.

In the operation of the apparatus as described above, and in the referred-to patent, difficulty is experienced in regulating the generation of steam to provide an 15 approximately uniform pressure due to the evaporation of the mercury in the vessel 23, with a consequent loss where the mercury vapor is exhausted into the atmosphere.

According to the present invention, I 20 overcome these objections by the following described appliances, comprising a receptacle 32 preferably depending from the vessel 23, as by means of a pipe 33 connected to but having no communication through the fitting 25. Adjacent to the upper end of the pipe 33 is a small hole 34 opening into the external atmosphere, and below said hole the pipe 33 is connected by a second pipe 35 with the upper end of the vessel 23, desirably by means of an elbow 36 coupling the pipe 34 to the pipe 23, as shown.

A cock 37 may be provided in the bottom of receptacle 32 for withdrawing mercury collected therein; or the same may be accomplished by detaching the receptacle 35 from the suspending pipe 33.

In operation, the vapor from mercury in vessel 23 escapes through the hole 24 and pipe 23¹ into pipe 35, in which the vaporized mercury condenses and descends in the 40 form of a liquid through pipe 33 into the receptacle 32. The hole 34 affords admission for air into the apparatus to retain an atmospheric pressure, or nearly so, in the vessel.

sel 23, receptacle 32 and in the pipes con- 45 nected therewith.

What I claim, is:—

1. In a damper-regulating apparatus of the character described, the combination with a liquid reservoir, a vertically movable 50 vessel into which a liquid is elevated by steam pressure from said reservoir, of a receptacle located below said vessel and arranged to reciprocate in unison therewith, and pipes affording communicative connec- 55 tions between said receptacle and the vessel.

2. In a damper-regulating apparatus of the character described, the combination with a liquid reservoir, a vertically movable 60 vessel into which a liquid is elevated by steam pressure from said reservoir, of a receptacle located below said vessel, and pipes affording communicative connections between said receptacle and the vessel, one of said pipes being provided with an opening 65 into the external atmosphere and disposed outside of the communicative connections between the vessel and receptacle.

3. In a damper-regulating apparatus of the character described, the combination 70 with a liquid reservoir, a vertically movable vessel into which a liquid is elevated by steam pressure from said reservoir, of a receptacle located below said vessel and arranged to reciprocate in unison therewith, 75 and pipes affording communicative connections between said receptacle and the vessel, one of said pipes being provided with an opening into the external atmosphere and disposed outside of the communicative connections 80 between the vessel and the receptacle.

Signed at Chicago, Illinois, this 3rd day of February, 1919.

ISAAC A. BACKLUND.

Witness:

I. GREEN.
